UNITED STATES PATENT OFFICE.

WALTER J. WARDER, JR., OF CHICAGO, ILLINOIS, ASSIGNOR TO THE ADAMS & WESTLAKE COMPANY, A CORPORATION OF ILLINOIS.

ELECTRIC SIGNALING DEVICE.

1,073,192.

Specification of Letters Patent. Patented Sept. 16, 1913.

Application filed November 6, 1911. Serial No. 658,790.

To all whom it may concern:

Be it known that I, WALTER J. WARDER, Jr., a citizen of the United States, and resident of Chicago, county of Cook, and State 5 of Illinois, have invented certain new and useful Improvements in Electric Signaling Devices, of which the following is a specification, and which are illustrated in the accompanying drawings, forming a part 10 thereof.

The invention relates to electric signaling devices adapted for railway service, its object being to provide a plurality of incandescent bulbs so as to be automatically brought into service and automatically shifted 15 in position to substitute a perfect bulb should the one in service become disabled, as by the breaking of its filament.

The invention consists of a shiftable carrier provided with a plurality of bulbs, a spring for holding the carrier in one of its positions, and means controlled by an electro-magnet, which, in the present instance, acts directly in opposition to the spring and 25 is controlled by one of the bulbs. In one form which the invention may take, and which is made the subject of a companion application, the magnet controls a detent for holding the bulb carrier against the action 30 of the spring.

The invention as hereinafter described is illustrated in the accompanying drawings, in which—

Figure 1 is a plan section of a lamp taken 35 through its lens; Fig. 2 is a bottom plan view of the casing for carrying the bulbs and housing the shifting mechanism; Fig. 3 is a plan view of the casing showing the bulbs mounted thereon; Fig. 4 is a diagrammatic view showing the preferred form of 40 controlling mechanism; and Fig. 5 is a diagrammatic view showing a modified form of construction.

The body of the lamp may be of any desired 45 form, being shown at 10 as of the design usually followed in semaphore lamps, its lens being represented at 11. Within the lamp body there is placed a casing 12 for supporting the bulbs and housing the controlling mechanism.

The bulbs 13, 14, are fitted to sockets 15, 16, mounted upon an oscillating plate 17 fixed upon the upper end of a tubular shaft 18, which is vertically journaled through

the top of the casing 12. A pinion 19 is 55 fixed upon the lower end of the shaft 18 and is engaged by a rack-bar 20 pivotally attached to an oscillating armature bar 21, which co-operates with an electro-magnet here shown as comprising a pair of spools 60 22. The armature is retracted by means of a spring 23, thereby normally holding the bulb 14, which may be designated as the auxiliary bulb, in service position, that is to say, upon the axis and at the focus of the 65 lens 11.

The line wires 24, 25, enter the body of the lamp through a suitable aperture, as 26, and lead to a pair of binding posts 27, 28, fixed upon the casing 12. A line 29 leads from 70 one of the binding posts 27 and, branching at 30, leads thence to both of the bulb sockets. From the socket of the bulb 13, which may be designated the main bulb, there leads a return line 31 through the coil of a 75 relay 32, and thence to the other binding post, as 28. The return from the socket of the bulb 14 is through a line 33 to a switch arm 34 fixed upon the shaft 18, and co-operating with a brush 35 suitably anchored 80 to the wall of the casing 12, and from which there leads a line 36 to the binding post 28. A line 37 leads from the binding post 27 to the fixed member 38 of a circuit breaker, the other member 39 of which is carried by the 85 armature 40 of the relay 32. A line 41 leads from the member 39 of the circuit breaker to the electro-magnet 22, and thence to the binding post 28. The armature 40 being normally retracted by means of a spring 42, 90 the local circuit through the electro-magnet 22 is normally open.

Upon the closing of the main line current is initially delivered to both bulbs. The return line from the main bulb 13 energizes 95 the relay 32, thereby closing the circuit of the electro-magnet 22, which immediately attracts the armature bar 21, thereby turning the shaft 18 to throw the auxiliary bulb 14 out of and the main bulb 13 into the 100 position of service and opening the circuit of the auxiliary bulb by withdrawing the switch arm 34 from engagement with the brush 35.

Should current cease to flow through the 105 bulb by reason of the breaking of its filament, or from other cause, thereby opening its branch of the circuit, the relay 32 is de-

energized, the circuit of the electro-magnet 22 is opened, thereby permitting the spring 23 to retract the armature bar 21 and turn the shaft 18 to shift the bulb 13 out of and the bulb 14 into the position of service, the same action closing the circuit of the latter bulb. If either bulb is in operative condition, the other being defective, it will assume the service position, as the auxiliary 10 bulb is normally at this position and the main bulb is instantly brought thereto if it will carry the current.

In the construction illustrated in Fig. 5, the relay 32 is dispensed with, the return 15 line 43 from the main bulb 13 leading through the coils of the electro-magnet 22. In other respects the mechanical and electrical arrangement of the parts is the same. This latter construction is serviceable in connection with bulbs using a current of large 20 volume; the construction first described renders the device serviceable in connection with lamps using a small volume of current, as the relay 32, which is in series with one 25 of the bulbs, has but little work to do.

I claim as my invention—

1. In an electric signaling device, in combination, a plurality of incandescent bulbs movable alternately to a given position, and 30 electro-magnetic means in series with one of such bulbs for controlling the movement of the bulbs.

2. In an electric signaling device, in combination, a plurality of incandescent bulbs, 35 a shiftable support for the bulbs movable to two positions and normally occupying one of such positions, and electro-magnetic means in series with one of the bulbs for

shifting the support to the other of such positions.

3. In an electric signaling device, in combination, an electric circuit, an oscillatable support normally occupying one of its extreme positions, an incandescent bulb mounted on the support, a switch connecting the 45 bulb with the circuit when the support is in its normal position, a second incandescent bulb mounted on the support and connected with the circuit, an electro-magnet in series with the second named bulb, and connection 50 between the support and the armature of the electro-magnet for moving the support from its normal position when the electro-magnet is energized.

4. In an electric signaling device, in combination, an electric circuit, an oscillatable support normally occupying one of its extreme positions, an incandescent bulb mounted on the support, a switch connecting the bulb with the circuit when the support is in 55 its normal position, a second incandescent bulb mounted on the support and connected with the circuit, an electro-magnet in series with the second-named bulb, a spring urging the support to its normal position, a gear mounted with the support, and a rack-bar connected with the armature of the electro-magnet and coöperating with the gear to move the support in opposition to the spring when the electro-magnet is energized.
